BARREL AGITATOR AND HANDLE

Charles E. Farrington, Phoenixville, Pa.

Application January 8, 1931, Serial No. 507,457

9 Claims. (Cl. 259—108)

This invention relates to improvements in stirring devices and has for an object to provide means for effectively agitating and stirring the contents of containers, which means may be easily and quickly assembled within and withdrawn from a container having a relatively small opening for the passage of the stirrer such as is found in a barrel or drum. One objection to certain devices heretofore in use arises because the stirring portion or blade contacts with the barrel during the stirring motion which causes a wearing off of the plating of the container employed to protect it from corrosion at the point of contact. Other devices heretofore used have not been rigidly secured in stirring position and consequently tended to rise from the bottom of the container when their use was attempted with masses of great density.

By means of the invention here described, I have provided a simple and efficient device which does not contact with the wall of the barrel and which is provided with means for locking the device in stirring position whereby any tendency to rise above the load to be agitated is avoided, and by which stirring may be effected completely throughout the mass to the bottom of the container and into the lower corners or chime portion thereof. I have also provided a new form of engagement of a handle with the stirrer bar which is rigid and positive in its operation and by which the handle may be quickly and easily attached or removed.

In the drawing,—

Fig. 1 is a side elevation partly in section showing the device with the handle attached, securely locked in operating position.

Fig. 2 is a fragmentary perspective view of a stirring device in position for insertion in the barrel or other containers.

Fig. 3 shows in fragmentary perspective the blades after insertion and before attachment to the bottom stud.

Fig. 4 shows in perspective, the adjacent blade portions with the latch in operative position.

Fig. 5 is a fragmentary perspective view showing the relation of the blades in Fig. 4 with the latch member raised.

Fig. 6 shows in perspective the handle in operating position, the upper end of the stirrer bar shown by dotted lines.

Fig. 7 is a diagrammatic view partly in section showing the method of insertion of the handle into the bunghole of the barrel or drum for engagement with the blade.

Paints and liquids of like character are com-

monly shipped in steel barrels or drums which in many instances are plated to prevent corrosive action of the contents upon the container. In the drawing a barrel or drum 1 is illustrated. In one head or end of this drum a central bunghole 20 is provided, the edges of the bunghole being threaded to receive the usual screw threaded cap with a hexagonal head. Projecting inwardly from the opposite head of the barrel 1 provide a central stud 2, threaded to receive a nut 2a. The stirrer is articulated, being formed of two blades, a lower blade 4 and an upper blade 7, these blades being pivotally connected together as at 8. The inner end 3 of the lower blade 4 is formed to fit rotatively and loosely over the stud and to be held thereon by nut 2a. The lower blade 4 normally is arranged approximately parallel with the bottom of the barrel, its lower edge extending close to the barrel head in its rotation but normally not in contact therewith. The lower blade extends outwardly close to the barrel wall and is formed with a square end at the lower outer corner. Near the outer end of the blade 4 two notches 5 are provided in its upper edge to receive a locking device or latch 6. The blade 4 is pivotally secured to the substantially vertical blade 7 as by means of a rivet 8, said rivet permitting a scissor-like movement of the blades. The latch 6 is preferably formed as a rectangular loop loosely surrounding the lower end of the blade 7 and so dimensioned that it easily drops into the slots 5 and thereby effectively locks the two blades in position at substantially right angles to each other. The bar 7 is preferably helicoidal, the lower portion extending upwardly approximately one-half of the height of the barrel in vertical position so that this portion of the blade will swing close to but out of contact with the lower half of the side wall of the drum. The upper half of the blade is bent and twisted for greater facility in its mixing operation and extends up into the bunghole of the barrel but does not project out above the upper edge of the hole. I prefer to employ the locking latch as shown and described, but it is obvious that a bolt and socket or a ring and pin or various other forms of locks or latches may be substituted without departing from this invention.

The stirrer may be inserted after the barrel is assembled by disengaging the latch from the slots and freeing the blade 4 from engagement with the latch, whereupon the blades may be turned into substantially aligned position and easily inserted through the bunghole into the barrel.

The lower blade 4 may then be turned on the pivot 8 to a position at right angles to the upper blade, and locked in that position by moving the latch 6 into the notches 5. The blades are then raised and the heel end 3 of the blade 4 may then be slipped over the stud 2 and lowered thereon and may be retained there as by a nut 2a threaded onto the end of the stud. A lock nut may also be employed to secure the nut 2a, especially in case the blade is to be rotated in an anti-clockwise direction. These nuts may readily be supplied to the stud as by an elongated socket wrench inserted through the bunghole. The barrel or drum is then ready to be filled with paint or other material for shipment. To remove the blade, I unscrew the nut 2a, whereupon the blade may be lifted from the bottom of the barrel and to a point adjacent to the bunghole and the latch may be disengaged from the locking position and the blade 4 swung downwardly, and the blade easily removed from the barrel so that the barrel may be cleansed. It will be seen that when the blade is secured in operating position by the locking latch that the stirring operation may be performed without an upward movement of the horizontal blade and that the latch effectively holds the horizontal blade in any desired position relative to the bottom of the barrel. I prefer to cut the notches 5 at such an angle and in such relation to the pivot 8 that the blade 4, when locked in position, will sweep closely to the bottom of the barrel but not in contact therewith. Thus the material which tends to adhere or collect in the lower corner of the barrel is effectively agitated and removed therefrom by the rotation of the stirrer blade.

I prefer to effect the rotation of the blade by means of a crank handle 9 of the form shown. The stirrer engaging portion of the handle is so formed as to be held firmly in operation by the walls of the bunghole and is slotted to receive the upper end of the blade 7 as at 11. It is usual to form the bunghole with a flanged threaded sleeve member as shown which may be securely welded or otherwise secured to the top of the barrel. The threaded member is adapted to receive the useful screw cap having a hexagonal head. When the cap is unscrewed and the handle inserted the threaded sleeve may act as a journal member preventing lateral movement of the engaging portion of the handle. I provide a lip or projection 10 at the end of the handle which is adapted to engage with the inner surface of the head adjacent to the edge of the bunghole. Adjacent to the lip portion, the handle is notched to receive the upper end of the stirrer blade 11, the outer portions of the legs of the notch 12 and 13 being dimensioned to fit snugly within the bunghole 14. I prefer to extend the stirrer bar up flush with the top of the bunghole and to construct it of material sufficiently rigid to resist its displacement downwardly by the handle thus insuring a close contact of the stirrer bar within the notch.

I claim:

1. A stirring device adapted to be secured to the center of the bottom of a container having a bunghole at the opposite end thereof, said stirrer comprising two flat blades, the lower blade being pivotally secured at its outer end to the upper blade, the upper blade being twisted helically upwards to the top of the bunghole, and means for locking said blades in right angle relation for operation, said locking means being

releasable for the removal of the blades from the container.

2. A stirring device adapted to be secured to the center of the bottom of a container having a bunghole at the opposite end thereof, said stirrer being composed of two flat blades, the lower blade being pivotally secured at its outer end to the upper blade, the upper blade being twisted helically upwards to the top of the bunghole, and means for locking said blades in substantially right angle relation, said locking means being releasable to permit the removal of said stirrer blade from the container.

3. In combination, a container having a bunghole and provided with a stud at the lower central portion, a flat horizontal blade rotatively attached to said stud and extending outwardly adjacent to the bottom wall of the container, a flat blade pivotally secured to the outer end of said horizontal blade and extending upwardly into the bunghole of said container, a detachable crank handle having a slot engaging the end of said upwardly extending blade within the bunghole, said handle being provided with a projection extending under the rim of the bunghole of said container and being journaled therein.

4. In combination, a barrel having a bunghole, an articulated stirring device insertible and removable through said bunghole, said stirring device comprising a pair of pivotally connected members, one member being horizontally adjacent to the bottom of the barrel, the other member having a lower portion disposed substantially vertically adjacent to the side of the barrel and an upper portion extending to the said bunghole, and means for locking said members in substantially right angle relation, said stirring device being journaled for rotation in the bunghole.

5. In combination, a barrel having a bunghole, an articulated stirring device insertible and removable through said bunghole, said stirring device comprising a pair of blades pivotally connected, one blade extending horizontally adjacent to the bottom of the barrel and nearly to the wall thereof, the other blade extending vertically adjacent to the side of the barrel for approximately half its length, then toward said bunghole, and releasable means for locking said blades in substantially right angle positions.

6. In combination with a barrel having a central bunghole sleeve, an articulated stirring device insertible and removable through said bunghole, comprising two blades, the lower blade being pivoted at the bottom of said barrel, the upper blade being pivotally attached to the lower blade at the outer end thereof and provided with releasable means for locking said blades in substantially right angle relation, the upper blade extending upwardly along the side of the barrel and toward the bunghole, a crank handle having a portion adapted to engage the inner end of the sleeve to prevent the handle from becoming disengaged in operation.

7. In combination, a container having a central bunghole at the top thereof, a stirring device composed of two blades pivotally joined together, one blade being adapted for support adjacent to the bottom of said container and pivoted at the center of said container at the bottom thereof, said blade being provided with notches at the upper outer edge, the other blade extending upwardly adjacent the side of said container, and bent toward the bunghole, and with latching means at the lower end to cooperate with the notches of the lower blade to support said lower

blade at substantially right angle relation, said stirring device being journaled within the bung-hole, a crank handle adapted to rotate said blades, having means to prevent said blades from rising 5 out of the bunghole in operation.

8. In combination, a container having a bung-hole with a surrounding rim, a stirring blade having a rectangular flat upper end portion extending into said bunghole, a crank handle, said handle in operating position being provided at its outer end with an upwardly extending handle, an arm portion, an axis portion loosely revoluble within the bunghole within which it is to be rotated, said axis portion being provided with a 15 slot adapted to receive and engage the end portion of said blade and having a horizontally ex-

tending lug opposite said arm portion adapted to loosely fit beneath the rim of the bunghole and be held down thereby.

9. In combination with a barrel having a bung-hole, an articulated stirring device therein, said device being insertable and removable through said bunghole and comprising a pair of pivotally connected members, one member being horizontally adjacent to the bottom of the barrel, the other member having a lower portion disposed substantially vertically adjacent to the side of the barrel and an upper portion extending to the said bunghole and means for locking said members in substantially right angle relation.
